(57) **CLAIM**

The ornamental design for a tape dispenser, as shown and described.

DESCRIPTION

FIG. 1 is a perspective view showing the new design for a tape dispenser;

FIG. 2 is a left side view thereof;

FIG. 3 is a right side view thereof;

FIG. 4 is a rear view thereof;

FIG. 5 is a bottom view thereof;

FIG. 6 is a front view thereof;

FIG. 7 is a top view thereof; and,

FIG. 8 is a perspective view thereof showing the tape dispenser with a tape.

The portions of the tape dispenser shown in broken lines form no part of the claimed design.

1 Claim, 5 Drawing Sheets

FIG. 1

FIG. 2

FIG. 3

FIG. 4**FIG. 5**

FIG. 8
